UNITED STATES PATENT OFFICE.

HUGH L. WARNER, OF DAYTON, OHIO, ASSIGNOR TO GEO. N. BIERCE, OF DAYTON, OHIO.

RUNNING-GEAR FOR VEHICLES.

SPECIFICATION forming part of Letters Patent No. 730,991, dated June 16, 1903.

Application filed July 3, 1902. Serial No. 114,173. (No model.)

To all whom it may concern:

Be it known that I, HUGH L. WARNER, a citizen of the United States, residing at Dayton, in the county of Montgomery and State 5 of Ohio, have invented certain new and useful Improvements in Running-Gear for Vehicles; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to improvements in the running-gear of motor-vehicles, and has special reference to that class of gears which are driven from the rear.

Generally speaking, the object of the invention 20 is to provide a running-gear many of the parts of which are interchangeable, so that the same patterns may be used for both sides of the gear and the cost of construction be thereby reduced.

25 A further object of the invention is to avoid the use of bent or curved parts in the construction of the gear in order that the greatest possible strength may be obtained.

A further object of the invention is to provide 30 ways and means for mounting the differential-gear case on the rear frame in a central position or on either side of a central position, so that the running-gear may be adapted to a variety of different styles of vehicle-bodies.

35 A further object of the invention is to avoid connecting the reaches to the front and rear tubular members in the usual manner, but by jointedly mounting the said reaches on standards by means of ball-and-socket bearings, as will be hereinafter more fully described.

Preceding a detail description of the invention 40 reference is made to the accompanying drawings, of which—

45 Figure 1 is a rear perspective view of my improved running-gear. Fig. 2 is a top plan view of the running-gear, parts of the reaches being broken away and the wheels removed. Fig. 3 is an enlarged vertical section on one 50 side of the rear half of the running-gear, showing both brackets of the differential-gear

case in section and the dust or gear case in elevation. Fig. 4 is an outside end view of the differential-gear case, one of the dust-cases being detached and removed to one 55 side. Fig. 5 is a vertical longitudinal section through several modified forms of blocks which form the top and bottom separators or distance-pieces for the differential-gear brackets. Fig. 6 is a vertical longitudinal 60 section through one of the reach ends, showing the upright standard, the brace, and bearings in a normal state. Fig. 7 is a similar view showing the other end of the reach and frame raised up, as is the case in traveling 65 over uneven ground. Fig. 8 is a sectional view in detail of one of the front pivot-axes. Fig. 9 is a top plan view of one of the pivot-axes.

In a detail description of the invention 70 similar reference characters indicate corresponding parts.

From Fig. 1 it will be seen that the front and rear framework of the running-gear constitute more than a mere axle and an axle-casing and that each end is composed of a strong form of bridge-work consisting of upper supporting members B and B', arranged in parallel relation to lower truss members A and A', and that the outer ends of said 80 members are strongly anchored in bearing-brackets F and F', which have parallel sockets H⁶ and H⁷, adapted to receive the frame members A and A', B and B'. It will be readily seen that in the construction of this 85 gear the members A and A', B and B' may be somewhat longer or shorter and the width of the frame altered to suit the required wheel-track without involving any change of parts and that such change in width or length can 90 easily be made when desired.

D⁵ designates the reaches, which connect the front and rear frames of the running-gear. The reach ends D⁴ are jointedly mounted in the standards C by means of a male and female bearing D⁷ and C⁸, the latter consisting of a concavity in the standards C. (See Figs. 6 and 7.) The standards C are interposed between the top and bottom members A and A'; B and B'. The male end D⁷ of the reaches 100 has a substantial and durable socket-bearing in said standards C and are held in position

by a concave nut L and lock-nut C''. The male end D'' rests against a shoulder D⁶ on the end extension D' of the reach. The parts are neatly fitted, and the connections are 5 strong and devoid of any play that might cause objectionable noises, but at the same time admit of a desirable flexibility between the reaches D⁵ and the standards C, as shown in Fig. 7. The lower ends of the brace-roads 10 C' have substantially the same bearings.

D''' designates a male cone-bolt adjustably fitted in the lug M of the brace, and L' is a lock-nut which locks the cone-bolt when the proper adjustment is found. The cone of the 15 bolt D''' is provided with a socket-bearing C^X in a clip L'', similar to the bearing in the standard C for the reach end D⁴. The upper ends of the clips L'' are concaved, as at O, to suitably embrace the bottom of the 20 lower frame members A and A'. The opposite ends M' of the braces C' are fitted around the reach extensions D' and held in normal position by a sleeve D, which incloses the reach extensions D', and have a suitable 25 spring K to force said sleeve D away from the standard C, and thus keep the frame in its normal position, and at the same time, in case that either corner of the frame is lifted, the action will compress the spring K and 30 slide the sleeve D back toward the standard C, thereby making a very flexible brace-and-reach connection and at the same time a very rigid and durable gear. As will be seen, the standards C may be set at any de- 35 sired distance apart and the reaches D⁵ in this way set any desired width without changing the distance from the ground or altering any part of the construction. This is indispensable, owing to the fact that the public de- 40 mand requires a variety of widths in reaches.

I have found many cases where the differential gear was not wanted in the center of the frame. Therefore to meet these requirements I have provided a differential-gear 45 case which may be located in the center or at either side of the center, as will be seen in dotted lines in Fig. 1. The differential-gear case is of special construction and will be described as follows: The upper and lower parallel frame members A B and A' B' are connected to brackets E⁵, each of which has parallel sockets E' and E'', into which the inner 50 ends of the frame members are fitted. The sockets E' and E'' are connected by a web E⁶, the whole constituting a bracket of suitable strength. These brackets E⁵ are held apart by a separator or distance block E'', which is 55 adapted to the style and size of differential gear used. (The differential gear being no part of the present invention is not shown.) Several modifications of the distance-pieces E'' are shown in Fig. 5 and conform to the outline of the differential gear, which is shown in dotted lines within the distance-pieces. Said 60 distance-pieces may be made of any desirable width. The brackets E⁵ are held in place by suitable fastening devices, such as bolts E'.

On the front and rear sides of the brackets there are placed suitable dust-caps E E, which complete the differential-gear case. Fig. 4 70 shows one of these dust-caps detached and removed to one side. The dust-caps are fastened to the brackets E⁵ by any suitable means—such, for example, as screws, which penetrate ears E⁸ and openings E^X in the 75 brackets. The lower frame member A is adapted to receive the rear axle, usually divided as shown in dotted lines in Fig. 3. I have provided in the lugs I and E' of brackets F' and E⁵ suitable openings E⁹ and I'' for 80 bearings, and in practice I may use interchangeable bearings in these openings. The construction admits of a change of bearings, which may be made in a few moments. The lugs E' and I receive the rear axle H'', the 85 axle and the lower frame member A forming the lower part of the rear half of the running-gear, which has no direct connection with the reaches D⁵ other than through means of the standards C. The front lugs F have two parallel sockets H⁶ and H⁷, Fig. 8, adapted to receive the upper parallel frame member B, and an opening H⁸ at right angles to said sockets to receive the pivot member H³ of axle H'. H⁴ is a steering-lever rigidly connected to the part H³ of said axle by means of nut H⁵. 90

H⁹ is a rod connecting the steering-levers H⁴. Any steering device (not shown) may be attached to this connecting-rod. 100

The next feature in the construction of my improved running-gear relates to the spring-rests G and G', which may be placed any distance apart and yet not alter the height of the springs from the ground, and, further, 105 said spring-rests may be used at three points or more on the running-gear, as will be seen by the dotted lines in Figs. 1 and 2, where the spring-rests are indicated at G³ and G⁴. 110

Having described my invention, I claim—

1. In a running-gear for vehicles, upper and lower parallel frame members, brackets having upper and lower parallel sockets in which the ends of said parallel members are fitted, and vertical openings in said brackets, and angular pivotal axles mounted in said vertical openings, the axle portion of said pivotal axles being in alignment with the lower member of the two parallel frame members, substantially as set forth. 115

2. The combination of two substantially parallel frame members, brackets having upper and lower parallel sockets into which the inner ends of said parallel frame members are fitted, brackets constituting portions of a gear-case, and adapted to receive a bearing-box, said brackets having upper and lower parallel sockets into which the inner ends of said frame members project, and dust-proof caps united to said brackets and constituting the other portions of said gear-case. 125

3. In a running-axle for vehicles, the combination of upper and lower frame members, a power-transmitting member mounted on the

- lower frame member, and a differential-gear case provided with adjustable separator or distance blocks.
4. In a running-gear for vehicles, the combination of a differential-gear case, side plates or brackets having parallel sockets, separator or distance blocks, and removable dust-cases.
5. In a running-gear for vehicles, the combination of upper and lower parallel frame members, two alined axles, a differential gear mounted on their adjacent ends, a housing for said differential gear, the side walls of said housing providing substantially parallel sockets adapted to receive the inner ends of the frame members, and separator or distance blocks within said housing.
6. In a running-gear for vehicles, the combination of a front and rear frame each consisting of two parallel members, reaches connecting said front and rear frame, standards mounted on the ends of said reaches, and a swivel connection between said standards and reaches.
7. In a running-gear for vehicles, the combination of a front and rear frame each consisting of two substantially parallel members, two substantially parallel reaches interposed between said frames, and standards mounted between the parallel frame members, the ends of the reaches being mounted in said standards.
8. In a running-gear for vehicles, the combination of front and rear frames each consisting of two parallel members, reaches interposed between said frames, slidable sleeves inclosing the ends of said reaches, and yielding means controlling said sleeves.
9. In a running-gear for vehicles, the combination of parallel frame members, reaches connecting said frame members, slidable sleeves inclosing the ends of said reaches, and tension-springs inclosed within said sleeves.
10. In a running-gear for vehicles, the combination of frames, reaches connecting said frames, said reaches having yielding end connections, with springs therein, and braces connecting the ends of said reaches to the frame members.
11. In a running-gear for vehicles, the combination of frames, reaches connecting said frames, said reaches having flexible end connections consisting of a male and female joint and springs.
12. In a running-gear for vehicles, the combination of frame members, connecting-stands with openings therein, concave and convex surfaces concentric with said openings, and reaches having yielding ball-and-socket connections with said standards.
13. In a running-gear for vehicles, the combination of frame members, said frame members being parallel throughout their lengths, connecting-reaches, braces having one end provided with an opening to receive the reach, and the other adjustably connected to the frame.
14. In a running-gear for vehicles, the combination of a frame-brace, an adjusting-cone having a shank extending through one end of said brace, and means for locking the same to proper adjustment.
- In testimony whereof I affix my signature in presence of two witnesses.
